Int. Cl. D8—08

U.S. Cl. D6—86

FIG. 1 is a side view of a combined escutcheon plate and supporting post incorporating my new design.

FIG. 2 is a front view of the plate shown in FIG. 1, the surface texture on the right side being generally similar to the texture shown on the left side.

FIG. 3 is a sectional view taken along the line 3—3 in FIG. 2.

FIG. 4 is a sectional view taken along the line 4—4 in FIG. 2.

This application is a division of my co-pending application Ser. No. 216,871, filed Jan. 10, 1972.

I claim:

The ornamental design for combined escutcheon plate and supporting post, as shown and described.
